UNITED STATES PATENT OFFICE.

WILLIAM H. HART, OF NEW BRITAIN, CONNECTICUT.

DESIGN FOR A HINGE-LEAF.

SPECIFICATION forming part of Design No. 23,506, dated July 24, 1894.

Application filed April 10, 1894. Serial No. 507,042. Term of patent 14 years.

to all whom it may concern:

Be it known that I, WILLIAM H. HART, a citizen of the United States, residing at New Britain, in the county of Hartford and State of Connecticut, have invented and produced a new and original Design for a Hinge-Leaf, of which the following is a specification, reference being had to the accompanying drawing, forming part thereof, in which the figure is a front elevation of a hinge-leaf showing my design.

A designates a strap leaf of the ordinary tapering contour, rounded at its outer end as shown and having an ordinary knuckle *a*. In the body of said leaf at the wider end is a circular opening 3 and by the side thereof in a narrower portion is a second circular opening 4 and by the side of that in a still narrower portion a smaller circular opening 5 as shown. The end screw hole 7 is near the end of the strap, while the middle screw hole 8 is be-

tween the circular openings 4 and 5 as shown. The screw holes 9 at the wider end are formed near the top and bottom edges, above and below the openings 3, as shown.

25

In Fig. 2 I have shown a hinge in which the left hand leaf is of the ordinary rectangular form and the right hand leaf is of my design.

I wish it distinctly understood that I make no claim whatever to the design for the left 30 hand leaf of Fig. 2 but confine my design strictly to the strap form of leaf which appears in both sides of Fig. 1 and the right hand side of Fig. 2.

What I claim is—

35 The design for the strap leaf of a hinge, substantially as herein shown and described.

WM. H. HART.
